UNITED STATES PATENT OFFICE

123,786

DESIGN FOR A FLOWER TROUGH OR SIMILAR ARTICLE

Erna Reens, New York, N. Y.

Application September 21, 1940, Serial No. 95,263

Term of patent 3½ years

To all whom it may concern:

Be it known that I, Erna Reens, a citizen of the Netherlands, residing at New York city, in the county of New York and State of New York, have invented a new, original, and ornamental Design for a Flower Trough or Similar Article, of which the following is a specification, reference being had to the accompanying drawing, forming part thereof.

In the drawing

Fig. 1 is a side elevational view of a flower trough showing my new design;

Fig. 2 is a top plan view thereof; and

Fig. 3 is an end view.

I claim:

The ornamental design for a flower trough or similar article, substantially as shown.

ERNA REENS.
